INVENTOR

Charles H. Christie
By Archibald Martin,
attorney.

UNITED STATES PATENT OFFICE.

CHARLES H. CHRISTIE, OF BUTLER, PENNSYLVANIA.

GLASS-POLISHING APPARATUS.

Application filed November 16, 1926. Serial No. 148,690.

My invention relates to glass polishing apparatus, and particularly to the construction of polishing blocks for finishing plates of glass.

This invention constitutes an improvement upon that disclosed in my Patent #1,610,658, issued Dec. 14, 1926, which describes and claims a felt-supporting member that may be attached to or detached from a polishing block without disturbing the block. In said patent, the felt-holding member is disposed circumferentially of the block.

It is the purpose of the present invention to provide means whereby the felt-holding member is rigidly held against upward movement relative to the block, so that there will be uniformity in wear as between those portions of the felt beneath the block and those portions beneath the felt-holding member. Furthermore, by my improved arrangement, the effective polishing area of a given head is increased.

One form which my invention may take is shown in the accompanying drawing, where in Fig. 1 is a vertical sectional view of a polishing block embodying my invention, and taken on the line I—I of Fig. 2; Fig. 2 is a plan view of the apparatus of Fig. 1, and Fig. 3 is a cross sectional view showing a modification of the apparatus of Figs. 1 and 2.

I have shown my invention as embodied in a polishing block 5, preferably of cast iron, that is supported upon a stem 6. Usually a plurality of blocks and their stems are mounted upon a rotatable spider or polishing head and are bodily moved in annular paths about the center of rotation of the spider or cam, to polish glass that is moved beneath the same. In operation, the block 5 has idle rotative movement about its stem 6, by reason of its frictional engagement with the glass surface being polished.

The block 5 is connected to its stem 6 by means of a follower plate 7 of cast iron or the like which holds the central recessed portion of the block 5 against the ball-like lower end of the stem 6. The plate 7 is held in position by bolts 8 whose heads are supported in T-slots 9 in the block 5.

A polishing pad 10 of felt or similar material is provided and is removably applied to the block 5 by reason of the fact that it is held in clamping engagement with a removable ring 11, by means of an annular band 12. The pad 10 is assembled with said

band and ring by placing one of said members beneath and the other above the felt and forcing them into concentric relation, thus bending the edges of the felt to the position shown in Fig. 1. The parts 10, 11 and 12 form a unit that is detachably secured to the polishing blocks by means of a screw stud 13 threaded into said block and having its outer end extending into a recess formed in the ring 11. Diametrically opposite to the stud 13, the block 5 is provided with a recess 14, and a hole 15 within which is contained a locking pin 16. As shown in the drawing, one end of the locking pin extends through the opening 15 into a hole in the ring 11, the other end of the pin 16 lying in the recess 14 so that the outer end thereof is held in locking engagement with the ring 11. To release the ring 11 the inner end of the pin 16 is raised and the entire pin may then be slid backwardly into the recess 17 of the block. The left hand side of the ring 11 is then lowered and the ring with its contained pad 10 and the band 11 moved to the right to clear the stud 13.

It will be seen that the polishing block 5 need not be disturbed and that it is only necessary to carry extra pads 10 and bands 11 and 12 in assembled condition in order to quickly replace worn pads. Frequent changes of felt are sometimes required because chips of glass or foreign matter become imbedded in the felt.

The block 5 is provided with four bosses or projections 18 that extend across the upper edge of the ring 11, so that such ring will bear a portion of the weight of the block and be held against upward movement relative to the block, this for the reason that the block 5 is of very great weight relative to the ring 11. If the ring were not held down tightly against the glass, that portion of the felt directly beneath the body of the block 5 would be worn away quite rapidly and, owing to the small amount of pressure that would be exerted by the ring 11, the felt beneath the ring would not be subjected to very great friction, so that not only would there be an uneven wear of the felt, but a loss in the effective polishing area would result. The bosses 18 are spaced from the stud 13 so that there will be a minimum interference thereby to tilting and removal of the ring 11.

In Fig. 3, I have shown a modified arrangement wherein all of the parts, except

the block 5^a and the ring 11^a are substantially as shown in Figs. 1 and 2. In this modified arrangement, the block 5^a is undercut and the ring 11^a is inturned at its lower edge so that it is angular in cross section, and the lower flange of this angle fits within the cut-out portion of the block. The bottom face of such flange is flush with the bottom face of the block 5^a so that a portion of the weight of the block 5^a is imposed upon the ring 11^a and that portion of the felt beneath the ring is held in close contact with the glass.

I claim as my invention:

- 15 1. The combination with a glass polishing block, of a ring, a polishing pad supported by said ring and having its edge upturned and held against the periphery of the ring, and means for detachably securing said ring to said block, the block being provided with an integral portion overhanging and directly engaging an upper portion of said ring in order to rigidly support the ring against upward movement relative to the block.
- 20 2. Glass polishing structure comprising a block, a polishing pad, a supporting member for the pad disposed within the peripheral boundary thereof, and means for detachably securing said supporting member to said block, the said block being provided with an overhanging portion that extends for a substantial distance circumferentially thereof and rigidly holds said supporting member

against upward movement relative to the block.

35

3. Glass polishing structure comprising an annular block, a ring-like member adapted to loosely surround said block, a polishing pad, and means for securing said pad to said ring-like member, the said block being provided with an integral portion that rigidly holds said supporting member against upward movement relative to the block, and the said ring-like member being disposed within the peripheral boundary of said pad. 40

45

4. Glass polishing structure, comprising a block, a pad-holding member disposed against the side of said block, the bottom surface of the pad-holding member being flush with the bottom surface of the block, a 50 pad extending entirely across said bottom surfaces, and an integral shoulder on said block for rigidly supporting the pad-holding member against upward movement relative to the block.

55

5. Glass polishing structure, comprising a block, a pad-holding member disposed against the side of said block, a pad covering the entire lower surfaces of the pad-holding member and the block and means 60 rigidly connected to said block, for restraining said member against upward movement relative to the block.

65

In testimony whereof I, the said CHARLES H. CHRISTIE, have hereunto set my hand.

CHARLES H. CHRISTIE.
